METHOD OF MAKING RUBBER SHOES

Erasmus P. Hedolin, New Haven, Conn., assignor
to The Elm City Rubber Co., New Haven, Conn.,
a corporation of Connecticut

Application June 21, 1932, Serial No. 618,540

3 Claims. (Cl. 12—142)

This invention relates to shoes and more particularly to rubber shoes, the invention being particularly useful in the prevention of athlete's foot.

5 One of the objects of the invention is the provision of a novel, economical and efficient method for making rubber shoes.

Another object of the invention is the provision of a method for making rubber shoes without lasts or forms.

10 A further object of the invention is the provision of rubber shoes which will tensionally fit the ankles of the wearer so that the wearer's foot will not become wet and may therefore not be liable to infection.

Other objects of the invention will be appreciated by those skilled in the art upon a reading of the following specification.

The invention will be fully and comprehensively understood from a consideration of the following detailed description when read in connection with the accompanying drawings which form part of the application with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Fig. 1 is a side elevation of my improved rubber shoe.

25 Fig. 2 is a section taken on line 2—2 of Fig. 1, looking in the direction of the arrows.

Fig. 3 is a plan view of a blank from which the upper of the shoe is formed.

40 Fig. 4 is a sectional view of the open shoe taken substantially at the position indicated by the line 2—2 of Fig. 1.

Fig. 5 is a fragmentary perspective view showing the reenforcement of the throat of the shoe.

45 Fig. 6 is a plan view illustrating the step in my method of pressing or stitching the rear edges of the shoe upper together.

Fig. 7 is a similar view illustrating a step in my method of simultaneously trimming and pressing into adhering relation the upper and sole of the shoe.

50 Fig. 8 is another plan view showing the application of a reenforcing strip to the edges of the upper and sole.

55 Fig. 9 is still another plan view illustrating the

application of a reenforcing strip to the rear of the upper; and

Fig. 10 is an edge elevation of apparatus for use in performing the above operations.

Figure 11 is a section taken on line 11—11 of Fig. 1, with the shoe in open condition.

Referring to the drawings for a more detailed description thereof, the shoe comprises principally the upper 6 and the sole 7, the upper being formed from the blank shown in Fig. 3, which is 10 cut with a V-shaped notch in the middle of its back or rear portion to provide the entrance to the shoe. Both the upper and the sole are preferably formed of thin sheet rubber in the uncured state, the shoe being cured after the parts 15 are put together. Furthermore the upper 6 and the sole 7 are flat, and when cut are made a little larger than their final dimensions in order to allow for trimming.

In forming the shoe, the rear edge portions 8a 20 and 8b of the upper are secured together by pressure, for instance, by feeding them between a flat roller 16 and a slightly bevelled rotating wheel 17, as in Fig. 6. The sole and the upper are then placed together with their edge portions together 25 and run between said roller and wheel using the sharp edge of the latter as a cutting edge, as in Fig. 7, so that the trimming is performed along the dotted lines shown in said figure. The pressure of the bevelled wheel 17 on the uncured 30 sole and upper is effective to cause these parts to adhere. The trimming and affixing together of the sole and the upper are thus simultaneously accomplished, or, in other words, are effected in one operation. A reenforcing thin strip of 35 rubber 9 is then applied to the adjoining edges of the sole and the upper, pressure being employed in causing the uncured strip 9 to adhere to the upper and to the sole, it being understood that the mentioned strip is in contact with both 40 the upper and the sole. In performing this operation the parts are run between the roller 16 and wheel 17, as shown in Fig. 8, without using the cutting edge of the latter. The rear edge portions 8a and 8b of the upper may then be reenforced by affixing with pressure a reenforcing strip 10 of thin uncured rubber. The edges 11 and 12 adjacent the opening of the shoe are also preferably reenforced either by inturning or by means of a separate strip of thin uncured rubber. 45 The throat portion of the shoe is further preferably reenforced by means of a strip 15 of uncured rubber affixed by means of pressure.

In applying the above reenforcing strips by pressure, the roller 16 and wheel 17 may be 55

utilized, without using the cutting edge, to press the parts together, for instance as shown in Fig. 9, which illustrates the step of applying the re-enforcing strip 10 to edges 8a and 8b. Since the other reenforcing steps are accomplished in the same manner and their performance will be readily understood, it has not been deemed necessary to illustrate the same.

After the joining and the reenforcing have been accomplished, the sole is infolded so that the same is covered by the shoe upper, as indicated in Fig. 1. The shoes are then placed on trays and loaded into a vulcanizer for curing. The curing may be done in any preferred or usual manner.

The stocks in making the shoe of my invention may be of varying grades of rubber, which may include varying compounding ingredients and they may be of different colors or combinations of colors. Furthermore the stocks used may be either smooth or of a design finish and combinations of different designs for any or all of the parts may be employed and the gauge or thickness of the parts used may be varied as desired.

My improved method simplifies the process of manufacturing shoes of the character mentioned, it being possible to make such shoes on machines now used for manufacturing rubber bathing caps and aprons. The use of reenforcing strips enables a manufacturer to use stocks of various gauges which otherwise might not be employed and my improved method enables shoes of the character mentioned to be made without lasts or forms which results in a large reduction in equipment costs and corresponding reduced cost of manufacturing. Furthermore the use of a waterproof material and the fact that the ankle part of the shoes tensionally fits the wearer's

ankles effectively prevent the contraction of athlete's foot or similar infectious diseases. The shape of the patterns allows the shoes to be worn interchangeably, that is to say, a shoe will fit either the right foot or the left.

It is to be understood that shoes made in accordance with my invention may be formed of material other than rubber.

What is claimed as new and useful is:

1. The method of making shoes which includes forming a sole and an upper from uncured sheet rubber, simultaneously trimming and pressing into adhering relation said upper and said sole, applying and pressing a reenforcing uncured rubber strip into adhering relation to said upper and sole at the juncture thereof, and vulcanizing said shoe.

2. The method of making shoes which includes forming a sole from an uncured flat sheet of rubber, forming an upper from an uncured single flat sheet of rubber, the latter step including the formation of a recess in the sheet extending forwardly from the rear edge thereof to form the entrance to the shoe and joining by pressure the rear marginal edges of the upper located on opposite sides of said recess, pressing into adhering relation said upper and said sole, applying and pressing a reinforcing uncured rubber strip in adhering relation to said upper and sole at the juncture thereof, and vulcanizing said shoe.

3. The method of making shoes which includes forming a sole and an upper from uncured sheet rubber, pressing into adhering relation said upper and said sole, applying and pressing a reenforcing uncured rubber strip into adhering relation to said upper and sole at the juncture thereof, and vulcanizing said shoe.

ERASmus P. HEDOLIN.
